BUCKLE ATTACHING MACHINE

Arthur J. Lewis, Stratford, Conn., assignor to The
Baird Machine Company, Bridgeport, Conn., a
corporation of Connecticut

Application August 16, 1937, Serial No. 159,373

18 Claims. (Cl. 223—49)

This invention relates to new and useful improvements in machine tools, the specific application of the invention as herein disclosed being a buckle attaching machine, but the principles are applicable to other specific applications.

An object of the invention is to provide a press including means whereby the press is tripped a plurality of times for each complete cycle of operation and each time the press is tripped a different operation is performed but with the same set of tools.

Other objects and advantages will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a top plan view of a machine constructed according to the present invention;

Fig. 2 is a side elevational view thereof with parts broken away as along the line 2—2 of Fig. 1;

Fig. 3 is an end view looking from the right in Fig. 1;

Fig. 4 is a sectional view as along the line 4—4 of Fig. 3;

Fig. 5 is a plan view of the parts shown in Fig. 4 but partly broken away;

Fig. 6 is a plan view on a reduced scale of a lower die member;

Fig. 7 is an end elevational view of such die;

Fig. 8 is an enlarged sectional view taken as along the line 8—8 of Fig. 6;

Fig. 9 is a side elevational view of the lower die member, on the scale of Fig. 6, and showing parts of actuating means associated therewith;

Fig. 10 is a sectional view through the lower die member substantially on line 10—10 of Fig. 11 showing the movable parts thereof in their positions at the end of the first operation and showing the buckle in its second position;

Fig. 11 is a plan view of Fig. 10;

Fig. 12 is a view similar to Fig. 10 but with the buckle in its third position and with the die and punch positioned as at the end of the second operation, the section of the buckle being substantially on line 12—12 of Fig. 13;

Fig. 13 is a plan view of the buckle and web as in Fig. 12;

Fig. 14 is a section showing the die and punch

at the end of the third operation, the buckle being completely attached to the web, the action of the buckle being substantially on line 14—14 of Fig. 15; and

5 Fig. 15 is a plan view showing the buckle and web as in Fig. 14.

As above suggested, the invention is here disclosed by way of example as embodied in a machine for attaching buckles to webs. The buckle 10 generally designated 10 is of a type used on the shoulder straps of overalls and comprises a frame 11 having a depending loop portion 12 provided with an opening 13 to receive a supporting button, and attached or integral at one end with the frame is a center bar 14 having prongs 15 to grip the free end of a shoulder strap and adapted to have its free end portion held in a closed position against a stop 16 by means of a lug 17 on the frame. The details of the buckle 10 are fully set forth in patent to Mosgrove No. 2,015,863 of October 1, 1935.

The buckle 10 is applied to a web 18 by the machine generally designated 19 and comprising side frame members 20 and 21 in the rear end portions of which is rotatably mounted a shaft 22. Secured on such shaft between the frame members is a small pinion 23 having a laterally extending hub-like portion 24, and also about said shaft and engaging the end of said hub portion and maintaining the pinion in place adjacent the frame member 21 is a collar 25.

On shaft 22 laterally of the frame member 20 is a pulley and fly-wheel or driven member 26 freely turnable on the shaft and constantly driven 35 from any suitable source of power in any suitable manner, as for example by a belt (not shown) working in the groove 27. The driven member 26 carries pins 28 rigid with the member and projecting laterally therefrom toward the frame member 20 and arranged quite closely adjacent the shaft 22. Said shaft in its portion between frame member 20 and driven member 26 is provided with a slot 29 through which extends a dog 30 having its ends projecting at opposite sides of the shaft and being pivoted intermediate its ends on a pin 31 securing it to the shaft.

The pins 28 and dog 30 comprise parts of a one revolution clutch comprising means whereby the member 26 may under the control of an operator 50 be connected with the shaft 22 to impart a revolution thereto. A pin or plunger 32 located for longitudinal sliding movement in the shaft 22 has one end constantly bearing against the dog 30, and a coil spring 33 acting on said pin keeps it against the dog in such relation that the latter

is being constantly urged about its pivot pin 31 in a direction to have its end portion 30a engaged by a pin 28 so that the dog and thus the shaft 22 will be carried with the member 26.

Trip means controlling movement of the dog 30 is mounted on the outer side of the frame member 20 and comprises a latch bar 34 pivotally mounted intermediate its ends as on a stud 35. A coil spring 36 is connected at its upper end to the inner end of the bar 34 and at its lower end is anchored as on a pin 31, and such spring tends to maintain the bar in the position shown in full lines in Fig. 4 and to return it to such position when moved therefrom, it being noted that the bar forwardly of the pivot 35 is normally against a stop pin 38.

Bar 34 at the forward side of pivot 35 has a notch or opening 39 extending vertically therethrough and opening through its side which is against the frame member 20. At its forward end such bar is provided with a cam surface 40 leading up to a shoulder 41. A pull bar 42 extends through the notch 39 in latch bar 34, and in its forward edge such pull bar is cut away to provide a horizontal shoulder 43 normally overlying the upper edge of the latch bar immediately forwardly of the notch 39. In its normal position the dog 30 is held out of the path of travel of the pins 28 since the lower portion 30b of said dog has been moved against the cam surface 40 rocking the other end portion 30a of the dog away from the driven member 26 and bringing the cammed-out end portion 30b of the dog against the shoulder 41 of the latch bar as in Figs. 4 and 5.

Through any suitable means as the rod 44 the pull bar 42 is connected with a treadle or the like (not shown), and to have the machine function the operator working such treadle causes bar 42 to be pulled downwardly thereby rocking latch bar 34 to the dotted line position of Fig. 4. This takes the shoulder 41 away from the portion 30b of the dog resting against such shoulder whereby the spring pressed pin 32 rocks the dog to carry one of its projecting end portions into the path of movement of a pin 28. Such pin engaging the dog, the dog and shaft 22 are moved with the pin the shaft being rotated in the direction of the arrow 45 (Fig. 4). After a partial rotation of the shaft projecting end 30b of the dog engages the pull bar 42 and forces it rearwardly to the inclined dotted line position of Fig. 4 whereupon the shoulder 43 is no longer over any part of the bar 34 and its spring 36 rocks such bar back to normal position. The bar 42 has an elongated slot in which is a guide and pivot pin 42b carried on the frame, the bar being held on the pin by suitable washers 42c and cotter pins 42d. A spring 42e connected at one end to the bar and at the other end to the frame tends to move the upper end of the bar to the right as viewed in Fig. 2 or to the left as viewed in Fig. 4 about the pin 42b as a pivot and thus tends to shift shoulder 43 to a position to engage over the top of lever 40.

As the shaft completes a revolution the projecting end 30b of the dog rides on to the cam surface 40 rocking the dog against the action of the spring pressed pin 32 thereby carrying the end 30a of the dog out of the path of movement of pins 28. Immediately upon leaving the cam surface 40 the projecting end 30b of the dog engages the shoulder 41 of the bar 34 whereby the machine is stopped. Thus the shaft can make only one revolution on each tripping of catch or

lever 34, even though the operator may hold the treadle and bar 42 depressed after tripping the catch, and before the catch can be again tripped or released the treadle must be released and it 5 and bar 42 be allowed to return to their normal position. To assist in stopping the shaft and prevent it turning backward on a rebound when the driving connection between it and the member 26 is broken and the dog comes against shoulder 41, a friction is maintained on the hub-like extension 24 of the gear 23. This is accomplished by means of a bracket 46 secured to the frame as by bolt 47 and carrying a pad of friction material 48 urged against the hub 24 as by spring 49. The friction may be adjusted by adjusting bolt 47.

The frame side members 20 and 21 mount a second shaft 50 located forwardly of the shaft 22 and having secured thereto a large pinion 51 meshing with the pinion 23. In the present embodiment the ratio between pinions 23 and 51 is such that pinion 23 makes three complete revolutions for each complete revolution of the pinion 51 as there are three distinct operations in the present cycle, but the ratio may be varied depending on the number of operations to be performed in a cycle. Shaft 50 carries cams 52 and 53 which being rotated with the shaft serve to operate tools as will later be described.

Mounted on the forward portion of the machine frame is a lower die 54 secured in place as with a machine screw 54a and comprising a body or die block 55 having a vertical opening 56 therethrough toward its rear edge and through 30 which is operable a plunger 57. At its upper end plunger 57 has a work engaging portion 58, in the present instance forming a lifter for the center bar of the buckle, and intermediate its ends the plunger is provided with an elongated recess 59 into which extends the end of a bolt 60 limiting vertical movement of the plunger. A coil spring 61 arranged between the lower side of the body 55 and the head 62 of the plunger serves to normally retain the plunger in the retracted or lower position of Fig. 8 and tends to return it to such position when moved therefrom.

On the upper side of the body or die block 55 adjacent one edge thereof is secured, as by screws 63, a member 64 providing a side wall and at right angles to such member there is secured a stop 65 having overhanging lugs or fingers 66 for holding work as will appear, and on loosening of a screw 67 such stop 65 may be adjusted to accommodate the die to different sizes of work. A holder or gate 68 forming a swinging latch is arranged on the upper side of the body 55, it being pivoted at 69 whereby to be movable from the full line to the dotted line position of Fig. 6. A spring 70 anchored to the body as by screw 71 and to a stud 72 fixed to the holder serves to keep such holder in the full line position of Fig. 6 and to return it thereto when moved therefrom.

Forwardly of the plunger opening 56 an anvil 73 is provided on the upper surface of the body 55, and at the forward end of such anvil at opposite sides thereof openings are provided for the accommodation of guide and locating pins 75, and such body is also provided with an opening 76 for the accommodation of a safety device or stud 77.

Pins 75 and stud 77 are carried by a holder 78 including a cylindrical portion 79 and a head 80, the latter having a lip or undercut portion 81 for the control of the holder and the pins as will

appear. Here it is noted that stud 77 is secured in the holder by set screws or the like 82, whereby such stud is vertically adjustable with respect to the holder. For the accommodation of the holder the body 55 is provided with an enlarged chamber or recess 83 opening through the lower side of the body and in alignment with the opening 76 for the passage of the stud 77.

The upper tool or punch generally designated 84 is mounted on a head-like portion 85 of a lever pivoted at 86 and including a rearwardly extending arm 87 carrying a roller 107, the purpose for which will later be described. Head 85 is provided with a side recess 88 receiving a mounting block 89 of the punch, and such block is secured to the head as by screws 90 passing through elongated openings 91 in the block whereby the latter may be adjusted vertically relative to the head 85. The work engaging portion of punch 84 is designated 92 and has a channel in its upper side receiving the lower edge portion of block 89, and it is pivoted to such block on a pin 93. This pin is located toward the rear or inner end of the portion 92 and a spring 94 in a recess in block 89 and acting against a pin 94a carried by member 92 keeps the portion 92 normally at an angle to the block 89, and in this connection it is noted that in the normal position of the head 85 the punch 84 is inclined with respect to the die 54. This pivotal mounting permits the punch to engage the work evenly throughout the length of the punch even though it moves in an arc because it is carried by a lever pivoted at 86. A heavy coil spring 95 anchored at one end on a stud 96 on the head 85 and at its other end on a stud 97 rigid with the machine frame tends to retain the head in the position of Fig. 2 and to return it to such position when moved therefrom.

An arm 98 is arranged in the lower portion of the machine and is pivoted intermediate its ends at 99. It has a forward portion 100 extending under the die 54 and a rear portion 101 extending under the cam 53. The portion 100 of the arm carries an adjustable screw 102 secured in adjusted position, as by nut 103, and located to engage the head 62 of plunger 57 and raise such plunger against the action of spring 61 on operation of the arm, as will later more fully appear. Such portion of the arm also carries a threaded stud 104 held in desired relation to the arm, as by nut 105, and having a head 106 extending over the lip or undercut portion 81 of the head 88 of holder 78 as clearly shown in Figs. 2 and 9. With this construction it will be understood that the holder 78 together with the pins 75 and safety stud 77 will be moved in accordance with movement of the arm 98.

On the rear or inner end of the extension or arm 97 of the head 85 is a roller 107 constantly held against the cam 52 by the action of the spring 95. From this it will be apparent that as such cam 52 is rotated with the shaft 50, the arm 87 and head 85 will be rocked about the shaft 86 resulting in movement of the punch 84 toward and from the work.

The machine being constructed as described to apply a buckle 10 to a web 18 the operator slides a buckle on to the die 54 in such position that the prongs 15 of the center bar 14 of the buckle project upwardly. That is, the buckle is in an upside down position and its upper edge opposite the loop 12 is placed against the inner edge of member 64 and the tip of the loop portion 12 of the buckle is against the curved inner

edge 108 of the latch or holder 68 when the buckle is initially placed on the die.

The operator then pushes the buckle toward the stop 65 and the gate or latch 68 yields for this purpose due to its mounting on the pivot 69, and then as the tip of buckle portion 12 reaches the cutout 109 on the inner edge of such latch 68, the spring 70 moves the latch back to normal position with the tip of buckle portion 12 extending under an overhanging lip portion 68a of the latch and fitted into the recess 109. When this occurs the inner end of the buckle passes under the overhanging lugs 66 on the stop 65.

15 The buckle is thus held by the lugs 66 and the latch 68 against upward movement off the die and by the member 64, stop 65, and latch 68 against lateral movement on the die and against movement out of the die due to the reception of the tip of its portion 12 in the recess or cutout 109 in the latch 68. When thus positioned on the die the buckle has its center bar 14 located above the anvil 73 but with the rear portion of such center bar or the portion thereof attached 20 to the frame 11 disposed above the opening 56 in which the plunger 57 operates.

25 The buckles as received have their center bars 14 substantially closed or substantially in the plane of the frame as shown in Fig. 8. After the buckle is placed in the holding die on the machine, the operator draws the pull bar 42 downwardly to trip the latch 34 whereupon one revolution is imparted to the shaft 22 in the direction of arrow 117 Fig. 2. Such shaft will have 30 but one revolution imparted thereto irrespective of whether or not the operator holds the bar 42 down, since as above explained, during revolution of the shaft projecting end 39b of the dog 39 forces such bar to the inclined dotted line 35 position of Fig. 4, whereupon the spring 36 may return the latch bar 34 to normal position to catch the dog 39 and release it from a pin 28 at the end of a revolution of shaft 22.

40 The revolution of shaft 22 results in a one-third revolution of shaft 50 in the direction of arrow 118 Fig. 2 and during such one-third revolution the high point 110 of cam 53 rides against the end portion 101 of the arm 98 shifting such end portion downwardly and rocking the end portion 45 100 upwardly. Bolt 102 during such movement of bar 98 engages the plunger 57 and forces it upwardly whereby its portion 58 engages the center bar 14 of the buckle opening such center bar or bending it upwardly to the position of Fig. 10. As 50 such one-third revolution of shaft 50 continues, the high point 110 of cam 53 rides off the end portion 101 of arm 98 and the spring 61 about the plunger retracts the latter to the position of Fig. 10 and rocks the forward end of the arm 100 55 downwardly.

60 As the plunger was elevated, so also was the holder 78 together with the guide and locating pins 75 and the safety stud 77. Such parts were elevated to the dot and dash line positions of Fig. 65 10, and as the plunger 57 was retracted by spring 61 the holder 78 and the parts thereon was also retracted since such holder is attached to the stud 104 as above explained. However, the holder 78 was not fully retracted since now the cam 53 is in the position of Fig. 2 with the portion 101 of arm 98 against the concentric portion 111 of the cam. This maintains the holder 78 in position with the guide and locating pins 75 and the 70 stud 77 projecting as in the full line positions of 75

Figs. 2 and 10. This is the position of the parts at the end of the first operation of the cycle.

The center bar of the buckle now being open the operator moves the web 18 laterally or edge-wise passing it under such guide bar as suggested by arrow 119 Fig. 11 and bringing its outer edge to the inner sides of the guide pins 75 as shown best in Figs. 10 and 11. These guide pins keep the web from overlying the stop 16 so that later when the center bar is moved downwardly against said stop, no portion of the web will intervene. These pins 75 also act as locating pins for the buckle as it will be seen from Fig. 11 they are located at the inner edges of the side bars of the buckle frame, and are also in the recesses 10a at the inner side of the outer end bar of this frame. During the described first one-third revolution of shaft 50 cam 52 has of course moved with such shaft, but during the 120 degree movement of the cam the roller 107 was riding against the concentric portion 52a of the cam so that no movement was imparted to the lever 37. This movement moves cam 53 through the 120 degrees indicated by arc 114.

The next time the machine is tripped, shaft 50 is given another one-third revolution near the end of which the cutout 113 of cam 53 moves over the inner end of arm 98 whereby such arm may rock an additional distance about pivot 98 further lowering the end 100 and drawing the guide pins 75 into the die 54. During this same time cam 53 is moving through a second 120 degrees designated by arc 115 in Fig. 2. During this time a comparatively high portion of the cam 52 indicated at 52b passes under the roller 107 causing the head 85 to be rocked about shaft 86 to move the punch 84 toward the buckle. Such movement carries the punch into the position of Fig. 12 pressing on the prongs 15 and pressing the center bar 14 of the buckle down on to the web 18 and holding it there. The prongs 15, however, are not bent down on to the bar and the operator can now insert the free end 18a (Figs. 13 and 15) of web 18 under these prongs into position for them to be bent down and clamped against the free end of the web to secure it to the buckle. It is now ready for the next operation.

The next time the machine is tripped the portion of cam 53 indicated by the 120 degree arc 112 passes over the end 101 of lever 98 permitting the pins 75 and 77 to be wholly withdrawn into the die block to the position of Fig. 14 as this lever rides on to the concentric portion 53a of the cam. At the same time the highest portion 52c of cam 52 moves up under the roller 107 causing a further movement of the punch toward the buckle and into the position of Fig. 14. However, before the machine is thus again tripped the operator doubles the web upon itself and inserts its end 116 under the prongs 15 on the center bar of the buckle as shown in Figs. 13 and 15, and as indicated above. Therefore, during the final downward movements of the punch 84 to the position of Fig. 14 (that is following the third tripping of the machine) such punch clinches the prongs 15 onto the end of the web. Also, this final movement of the punch results in the lug 17 being folded over onto the free end of center bar 14 by the recess 92a to lock such end of said bar against the stop 16 as shown in Fig. 14. Should it happen that the guide pins have not been retracted by action of spring 61 the portion 120 of the punch will, as the punch descends, engage safety stud 77 and force it and the guide

pins back into the die thus preventing breaking of such pins.

As the last one-third turning movement of shaft 50 continues, the high portion 52c of cam 52 moves from under the roller 107 whereupon the spring 95 acts to raise the head 85 and punch 84 to the original or starting position, and also the high portion 110 of cam 53 moves down toward the inner end of arm 98 ready to engage the same as the first step in the next complete cycle of operation of the machine.

From the above it will be understood that for each complete cycle of operation of the machine the latter is tripped three times and that each time it is tripped, a different operation is performed with the same set of tools. In the present instance, since there are three operations to be performed, the gearing between the shafts 22 and 50 is in such ratio that shaft 22 completes three revolutions to one revolution of shaft 50. That is, shaft 22 completes a revolution for each operation while shaft 50 makes only a partial revolution (one-third revolution in this case) for each operation and a complete revolution for each complete cycle. During the latter portion of the movement of shaft 50 on the third tripping of the machine, the punch 84 is being elevated and the completed work may then be removed from the die 54.

Having thus set forth the nature of my invention, what I claim is:

1. In a press, a set of tools for performing a series of successive operations on an article and comprising certain tools for one operation and certain tools for another operation, means whereby the press is required to be tripped a plurality of times for each complete cycle of operation, a cam shaft, means whereby said cam shaft is given a partial revolution only each time the press is tripped, cams on said shaft, and means whereby said cams actuate said tools in groups to perform a different operation each time the press is tripped during a complete cycle of operation of the machine, and said tools being constructed and arranged to hold the article in one position while the different operations are being performed.

2. In a press, means whereby the press is tripped a plurality of times for each complete cycle of operation, a cam shaft, means whereby said cam shaft is given a partial revolution only each time the press is tripped, first and second tools, a pair of cams on said shaft, means whereby on initial tripping of the press at the beginning of a cycle of operation one of said cams causes operation of the first tool, means whereby on the second tripping of the press the second cam causes operation of the second tool to and holds it in a new position, and means whereby on the third tripping of the press the second cam imparts further movement to the second tool.

3. In a machine of the character described, a shaft, a driven member, means operable to connect said shaft and member to have the former driven by the latter, means to automatically release said first means on the shaft completing a revolution, a second shaft, gearing between said shafts in such ratio that a revolution of the first shaft causes only a partial revolution of the second mentioned shaft, a pair of tools adapted for performing different operations on an article held in one position, a pair of cams on said second shaft, and means whereby said tools are actuated in predetermined order by said cams to perform said operations while the article

is held in said position as successive partial revolutions are imparted to said second shaft and to perform different operations by said successive partial revolutions of the shaft.

4. In a machine of the character described, a set of tools for performing a series of different operations in predetermined order on an article while the article is held in one position, a cam shaft, cams on said shaft, means actuated by said cams for causing said tools to perform said operations while the article is in said position, a second shaft, a driven member, a one-revolution clutch for connecting said second shaft with said driven member, means for automatically disconnecting said clutch at the end of each revolution, and said shaft being geared to said cam shaft in such ratio that while the cam shaft makes one revolution for the whole series of said operations the second shaft makes a revolution for each of said operations.

5. In a press, a set of tools for performing a series of different operations in predetermined order on an article held in one position and for each complete cycle of operation of the press, rotatable means operable during a single complete revolution for actuating said tools to perform all of said operations while the article is held in said position, a shaft, a driven member, a one revolution clutch for connecting said shaft with said member, means for automatically disconnecting the clutch at the end of each revolution, and said rotatable means being back-gearred to said shaft in such ratio that while such means makes one complete revolution during the performance of said operations by the tools said shaft makes a revolution for each of said operations.

6. In a machine for attaching to a web a buckle comprising a frame, a center bar having open prongs along its length and attached at one end to the frame, and a lug on the frame for anchoring to the other end of said bar, a die to receive and hold said buckle, a punch movable toward and from the buckle on the die, a plunger in the die, means whereby the machine is started and stopped three times during each complete cycle of operation, cam means, means whereby on the first starting of the machine the cam means actuates said plunger and the latter engages and opens said center bar for the insertion of a web laterally thereunder, means whereby on the second starting of the machine the cam means actuates the punch to have it move the center bar to closed position, and means whereby on the third starting of said machine the cam means actuates the punch to close said lug and said prongs.

7. In a machine for attaching to a web a buckle comprising a frame, a center bar having open prongs along its length and attached at one end to the frame, and a lug on the frame for anchoring the other end of said bar, a die to receive and hold said buckle, a punch movable toward and from the buckle on the die, a plunger in the die, and means whereby during a complete cycle of operation of said machine said plunger is actuated to engage and open the center bar of said buckle for the insertion of a web laterally thereunder, and the punch is actuated to move the center bar to closed position and then to close said lug and said prongs.

8. In a machine for attaching to a web a buckle comprising a frame, a center bar having open prongs along its length and attached at one end to the frame, and a lug on the frame for

anchoring the other end of said bar, a die to receive and hold said buckle, a punch movable toward and from the buckle on the die, a plunger in the die, means whereby on initial operation of said machine said plunger is actuated to engage and open said center bar of the buckle for the insertion of a web laterally thereunder, means to then retract said plunger, and means whereby on continued operation of the machine the punch is actuated to move said center bar to closed position and then to close said lug and said prongs.

9. In a machine for attaching to a web a buckle comprising a frame, a center bar having open prongs along its length and attached at one end to the frame, and a lug on the frame for anchoring the other end of said bar, a die to receive and hold said buckle, a punch movable toward and from the buckle on said die, a plunger in the die, means whereby during a complete cycle of operation of said machine said plunger is actuated to engage and open the center bar of said buckle for the insertion of a web laterally thereunder, the punch is actuated to move the center bar to closed position and then to close said lug and said prongs, and means for returning said plunger and said punch to their normal positions.

10. In a machine for attaching to a web a buckle comprising a frame, a center bar attached at one end to the frame and having open prongs along its length, and a lug on the frame for anchoring the other end of said bar, a die to receive and hold said buckle, a punch movable toward and from the buckle on said die, a plunger in the die, means whereby on initial operation of said machine said plunger is actuated to engage and open said center bar of the buckle for the insertion of a web laterally thereunder, means whereby on continued operation of the machine the punch is actuated to move said center bar to closed position and then to close said lug and said prongs, and means to thereafter raise said punch off the buckle.

11. In a machine for attaching to a web a buckle comprising a frame, a center bar attached at one end to the frame and having open prongs along its length, and a lug on the frame for anchoring the other end of said bar, a die to receive and hold said buckle, a punch, means pivotally mounting said punch for movement toward and from a buckle on the die, a plunger in the die, means whereby on initial operation of said machine, said plunger is actuated to engage and open said center bar for the insertion of a web laterally thereunder, and means whereby on continued operation of the machine the punch is rocked on its pivotal mountings to engage and close said center bar and then to close said lug and said prongs.

12. In a machine for attaching to a web a buckle comprising a frame, a center bar attached at one end to the frame and having open prongs along its length, and a lug on the frame for anchoring the other end of said bar, a die to receive and hold said buckle, a punch, means mounting said punch for movement toward and from a buckle on the die, a plunger in the die, guide pins movable through said die, means whereby on initial operation of said machine said plunger is actuated to engage and open said center bar for the insertion of a web laterally thereunder and said guide pins are projected to extend through the buckle frame and maintain an edge of the web away from said lug, and

means whereby on continued operation of the machine the guide pins are withdrawn into the die and the punch is moved to engage and close the center bar and then to close said lug on the free end of the center bar and clinch said prongs.

13. In a machine for attaching to a web a buckle comprising a frame, a center bar attached at one end to the frame and having open prongs along its length, and a lug on the frame for anchoring the other end of said bar, a die to receive and hold said buckle, a punch, means mounting said punch for movement toward and from the die, a plunger in the die, guide pins movable through the die, means whereby on initial operation of said machine said plunger is actuated to engage and open said center bar for the insertion of a web laterally thereunder and said guide pins are projected to extend through the buckle frame and maintain an edge of the web away from said lug, means whereby on continued operation of the machine the guide pins are withdrawn into the die and the punch is moved to engage and close the center bar and then to close said lug on the free end of the center bar and clinch said prongs, and a stud fixed with respect to said guide pins and arranged in the path of movement of said punch whereby should said guide pins stick said punch will engage said stud and force said pins back into the die.

14. In a machine for attaching to a web a buckle comprising a frame, a center bar attached at one end to the frame and having open prongs along its length, and a lug on the frame for anchoring the other end of said bar, a die to receive and hold said buckle, a punch, means mounting said punch for movement toward and from the die, a plunger in the die, guide pins movable through the die, a rockable arm, means to rock said arm on initial operation of the machine, said arm mounted to actuate said plunger to engage and open said center bar for the insertion of a web laterally thereunder, said arm connected with said guide pins to simultaneously with the actuation of the plunger shift said pins to positions extending through the buckle frame and maintaining the web away from said lug, spring means normally tending to retract the plunger and thereby rock said arm in the opposite direction and retract the guide pins into the die, and means whereby on continued operation of the machine said spring is permitted to so act and the punch is moved to engage and close the center bar and then to close said lug on the free end of the center bar and clinch said prongs.

15. In a machine for attaching to a web a buckle comprising a frame, a center bar attached at one end to the frame and having open prongs along its length, and a lug on the frame for anchoring the other end of said bar, a die to receive and hold said buckle, said die including an anvil portion below said center bar when the buckle is on the die, a punch movable toward and from the die, a plunger in the die, and means whereby during a complete cycle of operation of said machine the plunger is actuated to engage and open the center bar of the buckle for the insertion of a web laterally under said bar, and the punch is actuated to move the center bar to closed position and then to close said lug and clinch said prongs while the center bar is supported by said anvil.

16. A die for holding a buckle in a press comprising a body, a wall projecting above a surface of said body, a stop projecting above said surface and at right angles to said wall, ears on said stop and under which an edge of a buckle may pass, a holder on said surface, means pivoting said holder to said body for swinging movement in a direction away from said wall, a spring resisting such movement of the holder but permitting the same to yield on insertion of a buckle onto the die, and said holder including a portion to overlie an edge of a buckle on the die.

17. In a press, a set of tools for performing a series of successive operations on an article while held in a given position, means whereby the press is tripped a plurality of times for each complete cycle of operation, a cam shaft, means whereby said cam shaft is automatically given a partial revolution only each time the press is tripped, cams on said shaft, and means whereby said cams actuate different groups of said tools at different parts of the cycle of operation to have them perform a different operation each time the press is tripped during a complete cycle.

18. In a machine tool, a plurality of tools adapted to perform a series of different operations in succession on a piece of work during a given cycle and while said piece is held in one position, a cam shaft, cams on the shaft for operating said tools in different groups during different parts of a single revolution of said shaft for the respective operations, manually controlled means for starting said cam shaft for each said operation of the tools, and means for automatically stopping the shaft at the completion of each of said respective operations.
